UNITED STATES PATENT OFFICE.

JOHN H. PILLINGS, OF COLUMBUS, OHIO.

PRINTING-MACHINE.

No. 874,033.

Specification of Letters Patent.

Patented Dec. 17, 1907.

Application filed August 22, 1907. Serial No. 389,679.

To all whom it may concern:

Be it known that I, JOHN H. PILLINGS, a citizen of the United States, residing at Columbus, in the county of Franklin and State of Ohio, have invented certain new and useful Improvements in Printing-Machines; and I do hereby declare the following to be a full, clear, and exact description of the invention, such as will enable others skilled in the art to 10 which it appertains to make and use the same.

My invention relates to printing machines designed to reproduce or duplicate circular letters or other business printed matter in 15 large quantities, has for its object economy in time and labor, and the production of printed matter which shall be verily type written reproductions and duplicates without the possibility of an error in the matter.

20 The invention consists in certain improvements in construction whereby a number of forms of matter may be set up, and used separately as may be desired, without disturbing the type in the form, as will be fully disclosed in the following specification and claims.

In the accompanying drawings, which form part of this specification:—Figure 1 represents a plan view of a printing machine 30 embodying my invention, the carriage and the form of type being shown at the front end of the machine, and after the impression has been taken from the type the guide or support for the letter-head being removed. 35 Fig. 2 a side elevation of the same, the ribbon rolls being omitted. Fig. 2^a, a detail side elevation of one of the ribbon-rolls and its operating mechanism detached and on an enlarged scale. Fig. 3 a longitudinal section on line 3, 3 Fig. 1. Fig. 4 a transverse section on line 4, 4, Fig. 1. Fig. 5 a detail cross section, showing one side of the frame and the carriage, and the lever for operating the roll or platen in elevation and on an enlarged scale. Fig. 6 a like longitudinal section, showing the means for operating the roll or platen and the means for moving the carriage intermittently, the pawls in both instances being out of engagement with their respective ratchets. Fig. 7 a like view, the pawls for operating the roll and for moving the carriage being shown in engagement. Fig. 8 a top plan of the pawl for moving the carriage. Fig. 9 a top plan view of a section 50 of the chase with type in position. Fig. 10 an end view of section of the chase. Fig. 11

a side view of the same. Fig. 12 a plan of the carriage detached. Fig. 13 an end view of the same, and Fig. 14 a plan of a section of a modification of the carriage provided with recesses for the insertion of a chase containing type for an address and a chase containing type for a given date.

Reference being had to the drawings and the designating characters thereon, the numeral 1 indicates one side of the frame of the machine, 2 the opposite side, which sides are suitably secured together, and are provided with flanges 3, 3, which rest upon a base 4 and may be secured thereto by screws, not shown, and in each side of the frame is a longitudinal guide-groove 5, 5, to receive a longitudinally movable carriage 6, having projections 7, 7, thereon, which engage the grooves 5, 5.

The carriage is provided with an opening 8, on whose walls is an inwardly projecting member 9, which forms a support for a detachable plate or chase 10 in which the type 11 are set up and secured in position. The 80 chase is provided with rows of round holes 12 to receive the round shanks 13 of the type, and are properly spaced apart, the holes being equal to the number of characters in a full line of a letter written on a typewriter; 85 and the number of rows is determined by the length of the letter.

The type are provided preferably with a square upper portion to which the numeral 11 is applied, and on the outer end of which 90 the characters are formed, and are separated and prevented from turning in the chase by spacing-bars 14, which are detachably secured to the chase by dowel-pins 15, one at each end of the bars, and by springs 16 95 which are secured to the chase and engage the ends of the bars, as shown in Figs. 9, 10 and 11, and the type are held down to their seats on the chase by a spring 17, having resilient fingers 18, one for each type, secured 100 to each spacing-bar 14.

The chase 10 is removable from the carriage 6, to facilitate the setting of the type, and so that any number of forms may be set up and used interchangeably as may be desired, and thus avoid distributing the type, and again setting up the same matter. The carriage 6 is also provided with openings 19, and 20, the former to receive a chase containing an address, and the latter to receive 110 a chase containing the date of the letter. 21 indicates a shaft supported in the sides

of the machine and on one end of which is a cam 22, and adjacent thereto is a cylinder or drum 23 on whose periphery are arranged pins 24, one for each type in a line of maximum length set up in the form, which pins extend throughout one half of the circumference of the drum, and each pin engages a bell-crank lever 25, of which there are also as many as there are type in the line. The 10 bell-crank levers are supported on a transverse shaft 26 engaging the sides 1, 2 of the machine, and are arranged directly under the type in line, one lever for each type, and in the revolution of the drum 23, the pins 24 engage the short arms 27 of the several levers in succession and the long arms 28 of the levers strike the type and project them upward to effect the printing. The arms 27 are returned to their normal position to again 15 engage the pins 24 by a spring 27', one for each lever, secured to a transverse bar 28', and the arms 28 are supported on a bar 29'.

On a stub-shaft 29" secured to the side 1 of the frame, is a bell-crank lever 30, on one 25 arm 31 of which is a roller 32, which engages the cam 22, and the opposite arm 33 is provided with a pin 34, on which are parallel bars 35, 35, between which bars is a pawl 36 held up by a spring 37, and on the lower side 30 of the bars 35 is a projection 38, to engage a pin 39 on the side 1, and raise the pawl into engagement with a toothed rack 40 on the underside of the carriage 6, to move the carriage and the type forward intermittently 35 one line at a time as the shaft 21 and the drum 23 are revolved. The roller 32 is held in engagement with the cam 22 by a spring 41, one end of which is secured to a stud 42 on the side 1 of the frame, and the shaft 21 40 and the drum 23 are revolved by a crank 42' manually operated.

43 indicates the roll or platen mounted on a shaft 44, and on one end of said roll is a ratchet wheel 45 engaged by a pawl 46 45 pivotally secured to a lever 47, supported on a stud or pin 48 secured to one of the brackets 48' attached to the frame of the machine. The pawl is held in engagement with the teeth of the ratchet wheel by a spring 49, and the roll is revolved, the paper moved and spaced for printing by the end of the pawl 36 being projected against one end of the sliding bolt or pin 50, and its opposite end being projected against the adjusting screw 51 in the arm 52 of the lever 47. The lever 47 and the pawl 46, are drawn back for a new bite on the ratchet 45 by a spring 53, connected to the lever 47 and to a bracket 54 secured to the side 1, which is 55 provided with an adjustable screw 55 to limit the return stroke of the lever 47 and the pawl 46.

56, 57 indicate ribbon-rolls over which ribbon 58, travels at an angle across the machine to change position of the part of the

ribbon previously used. The rolls are supported on brackets, 59, 60, secured to the sides 1, 2 of the frame of the machine, and are operated by cams 61, 62 on the ends of the shaft 44, which engage levers 63, 64, respectively, supported on the shafts 65, 66, which extend through the rolls 56, 57, and are provided with pawls 58', 59', which engage ratchets 67, 68, on the respective ribbon-rolls. The levers 63, 64 are provided with 70 rollers 69, 70, which engage the working face of the cams 61, 62, and are held in engagement therewith by spring 71, on each arm, only one of which is shown, and the pawls 58', 59' are held in engagement with their respective ratchets, by spring 72, only one of which is shown. The ribbon is unwound from one roll and wound on the other, and when the latter is full, the operation is reversed, by throwing the opposite pawl in engagement with its roll, and the ribbon returned to the first roll, as in an ordinary typewriter. The ribbon 58 is supported between the type and the platen in suitable clips 73, 74, and the paper or letter-head to be written upon travels over a guide or support 75, and is pressed against the roll or platen by a rod 76, having rubber rolls 77, thereon and operated by a rod 78, lever 79 and spring 80. The chase with its form of type having been placed in the carriage 6, the carriage is drawn to the rear end of the machine by seizing the knob 81, the lever 42' is then seized by the hand of the operator, the drum 23 revolved, the type projected 95 against the ribbon throughout one line, when the carriage is moved forward intermittently, one line at a time, the paper on the roll or platen properly spaced and the operation continued until the letter has been completed. The foregoing operation being 100 repeated on as many different letter-heads as may be required. The chase may then be removed from the carriage and another chase containing a different form substituted 105 therefor, thus providing for the printing of many different forms of matter without disturbing the type in the chase.

It is obvious that changes may be made in details of construction, without departing 115 from the spirit of my invention.

Having thus fully described my invention, what I claim is

1. In a printing machine, separate movable type, a frame provided with longitudinal grooves, a chase supporting the type in alinement and movable in the frame, a lever for each type in a line, and means supported by the sides of the frame for operating said levers and projecting the type. 120

2. In a printing machine, separate movable type, a frame provided with longitudinal grooves, a carriage movable in said grooves, a chase supporting the type in alinement and engaging said carriage, a lever for 130

- each type in a line, and means for operating the levers and projecting the type, said means and said levers supported by the sides of the frame.
5. 3. In a printing machine, separate movable type, a chase for supporting the type in a plurality of parallel lines, a bank of levers comprising a lever for each type in a line and adapted to operate the type of each line consecutively, and means for operating said levers to project the type.
4. In a printing machine, separate movable type, a frame provided with longitudinal grooves, a carriage movable in said grooves, a chase supporting the type in alinement and engaging said carriage, a lever for each type in a line, and a revolute member arranged transversely of the frame, and supported by the sides of the frame, for operating said levers consecutively.
5. In a printing machine, separate movable type, a chase for supporting the type, a frame, a carriage supporting the chase and longitudinally movable in said frame, means for projecting the type consecutively, means for moving the carriage intermittently and a revolute member adapted to operate said means for projecting the type and the means for moving the carriage.
30. 6. In a printing machine, separate movable type, a chase supporting the type in alinement, spacing-bars between the lines of type, and springs for securing the bars to the chase; in combination with a carriage for supporting the chase and means for projecting the type consecutively.
7. In a printing machine, separate movable type, a chase supporting the type in alinement, spacing-bars secured to the chase, and means on said bars for holding the type between the bars; in combination with a carriage for supporting the chase, and means for projecting the type consecutively.
45. 8. In a printing machine, separate movable type, a chase supporting the type in alinement, spacing-bars detachably secured to the chase, and resilient members secured
- to said bars and engaging the type; in combination with a carriage for supporting the chase, and means for projecting the type 50 consecutively.
9. In a printing machine, a chase having holes therein in alinement, type having a square upper end on which the characters are formed and a round shank engaging the 55 holes in the chase, and spacing-bars between the lines of type; in combination with a carriage for supporting the chase, and means for projecting the type consecutively.
10. In a printing machine, a frame provided with longitudinal grooves, a carriage longitudinally movable in said grooves, a chase provided with movable type and detachably supported on said carriage, a revolute member supported in the frame, and 65 adapted to furnish power to advance the carriage and to project the type.
11. In a printing machine, separate movable type, a chase for supporting the type in alinement, a frame, a carriage supporting 70 said chase longitudinally movable in said frame, a transverse shaft between the sides of the frame, a plurality of levers supported on said shaft and adapted to engage the type, and a revolute member between the sides of 75 the frame engaging said levers to project the type.
12. In a printing machine; a frame provided with longitudinal grooves, a carriage longitudinally movable in said grooves, separate movable type, a chase supporting said type in alinement and detachably supported in said chase, levers for each type in a line, a platen, a revolute member supported in the frame and adapted to engage said levers, and 80 connections for advancing the carriage and revolving the platen synchronously.
- In testimony whereof I affix my signature, in presence of two witnesses.

JOHN H. PILLINGS.
